FLEXIBLE STORAGE CONTAINER FOR LIQUIDS

Lloyd I. Volckening, Glen Ridge, N. J., assignor to Ivers-Lee Company, Newark, N. J., a corporation of New Jersey

Application September 16, 1957, Serial No. 47,742

Term of patent 14 years

(Cl. D58—2)

Fig. 1 is a front elevational view of a flexible storage container for liquids, showing my new design;

Fig. 2 is a side elevational view thereof;

Fig. 4 is a horizontal cross sectional view thereof; taken on the line 4—4 of Fig. 1;

Fig. 5 is a horizontal cross sectional view thereof; taken on the line 5—5 of Fig. 1; and

Fig. 6 is a horizontal cross sectional view thereof; taken on the line 6—6 of Fig. 1.

I claim:

The ornamental design for a flexible storage container for liquids, as shown.
